JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

RACEWAY FOR STITCH-FORMING RECIPROCATING ELEMENTS.

1,086,607.

Specification of Letters Patent.

Patented Feb. 10, 1914.

Application filed April 30, 1913. Serial No. 764,594.

To all whom it may concern:

Be it known that I, JOSEPH M. MERROW, a citizen of the United States, residing at Hartford, in the county of Hartford, State 5 of Connecticut, have invented certain new and useful Improvements in Raceways for Stitch - Forming Reciprocating Elements; and I do hereby declare the following to be a full, clear, and exact description of the 10 same, reference being had to the accompanying drawings, forming a part of this specification, and to the characters of reference on the said drawings.

My invention relates to improvements in 15 the construction of raceways for the reciprocating elements of high speed mechanisms.

One object of my invention is to provide a raceway so constructed that the amount of wear resulting from high speed and continued use will be reduced.

Another object is to provide a simple and convenient construction whereby the respective parts of a number of raceways may be readily interchangeable.

25 Another object is to so construct a raceway that the relative alinement of the bearing surfaces thereof is easily assured, and a still further object is to incorporate all these features in a raceway having a reversible base plate, that may be readily applied to the frame caps of machines of the general types disclosed in United States Patents Nos. 441,315 and 591,049.

With these and other objects in view my 35 invention consists in certain novel and useful features and details of construction as hereinafter more fully described and more particularly pointed out in the claims.

In the drawings: Figure 1 is an isometric 40 view of an embodiment of my invention shown as applied to the frame cap of an overseaming machine of the well known Merrow type. The device is shown assembled and one of the gibbs has been partly 45 broken away to more clearly disclose the base of the raceway. Fig. 2 is an isometric view of the portion of the frame cap to which my invention is applied, showing the various parts detached but approximately 50 in their correct relative positions, the dot and dash lines indicating how each part is placed when assembled.

Referring to the embodiment shown in the drawings, the letter F denotes the frame

cap having the dove-tail raceway secured 55 thereto, the said raceway consisting in the main of the base plate B and the gibbs G and G' all preferably being made of suitable wear resisting material and being secured to a plain surface F' on the frame 60 cap by the screws g g and g' g'.

In the surface F' of a frame cap is often found a recess 30^b having an extension 30^c; and at a suitable distance above this recess and suitably disposed with respect to the 65 face F^a is the spline S. The aperture B' in size and form approximately corresponds to the recess 30^b and it is suitably located in the plate B to register with the said recess. The extended portion B² of this aperture, 70 however, unlike the extension 30^c which is off the center of the aperture 30^b, is centrally alined with the aperture B' of which it is an extension, and instead of corresponding in form with the extension 30^c 75 it is enough wider to clear the recess 30^c when the plate B is reversed, as will be hereinafter explained. Arranged on the opposite faces B³ and B⁴ of the plate B and on opposite sides of the longitudinal axis 80 of the aperture B' are the splines S² and S', parallel to the said axis and parallel to each other. The splines S' and S² are each set the same lateral distance from the longitudinal axis of the aperture B' as the 85 spline S is distant from the longitudinal axis of the recess 30^b.

In the under side G⁴ of the gib G is the spline S³ preferably arranged in parallelism with the intersection of the surfaces 90 G² G⁴. The holes for the screws that pass through the splines and that secure the gibbs G and G' in place are arranged to permit the reversal of the base plate. The two holes b² b² register with similar holes f² f² in the 95 frame cap and usually, they are arranged on the longitudinal axis of the aperture B'. Through these holes pass two screws for securing to the frame cap a piece not shown. In assembling this raceway, the keys k and 100 k', which should fit the width of the splines accurately but which should be somewhat shallower than the combined depths of the two alined splines, are inserted in the alined splines as S S' and S² S³, and between 105 the respective holes f' f' and b b, as shown in Fig. 2, and when the raceway is assembled as shown in Fig. 1, the whole is se-

- curely held together by the screws g g' and g g' , the base plate B being clamped between the faces G^3 and G^4 , of the gibs G and G' , and the face F' of the frame cap.
- 5 The gib G is accurately positioned by the keys and splines, and the gib G' which is adjustable to compensate for wear as set forth in Patent #441,315, is located in alinement with the gib G by a suitable adjusting wedge W which is secured to the frame cap by the screw w.

The faces B^3 and B^4 are parallel with each other and correspond respectively, and when the plate B is reversed by turning it 15 side for side on the longitudinal axis of the aperture B' , the face B^3 may be substituted for the face B^4 or vice versa. Thus if one face, for example the face B^3 , should become worn, it is only necessary to remove 20 the screws g g' and g g' , when the plate B may be turned with its worn face to the face F' , the splines S' and S^2 exchanging places and substituting one another, while the face B^4 presents a new wearing surface in place 25 of the surface B^3 .

The raceway herein described and shown is self contained and its gibs G and G' are mounted and bear wholly on an integral piece or plate that forms the bottom of 30 the raceway, the whole constituting a structure that may readily be made with accuracy and uniformity and that may be applied to any suitable support.

It is obvious that where the construction 35 of the support does not demand it, the aperture B' B^2 and holes b^2 b^2 may be omitted, and while I have described in detail the specific form and embodiment of my invention as shown in the drawings, I do not 40 limit myself thereto, but

What I claim and desire to secure by Letters Patent of the United States is:—

1. In combination in a raceway including a pair of gibs, a support therefor and a base 45 plate wholly interposed between the said gibs and the support; the base plate, the support and one of the gibs having means thereon for accurately alining the three, and means for securing the gibs and the 50 base plate to the support.

2. In combination in a raceway and with the support thereof, a base plate reversible face for face, a gib relatively fixed thereon, a second gib laterally adjustable with respect to the fixed gib, means for position- 55

ing and holding the gibs in alinement, and means for securing the gibs and base plate to the support.

3. In combination in a raceway, and with a support therefor, a pair of gibs, a base 60 plate for the raceway and for the gibs, corresponding splines in the support, in the base plate and in one of the gibs, keys for the said splines whereby the support, the base plate and the gib are held in the desired relative positions, and means for securing the raceway to the support.

4. In combination in a raceway mounted on a support, a spline in the support, a pair of gibs, one of which has a longitudinal 70 spline therein, a reversible base plate having a spline in each of its opposite faces, an aperture in the said base plate, the said aperture being suitably formed to clear a recess in the support, means for holding 75 the splines in alinement, and means for securing the raceway to the support.

5. A raceway including in combination, a pair of gibs, a reversible base plate, a support for the raceway, means for effecting 80 the alinement of the gibs, wear compensating means, and means for securing the raceway to the support.

6. In combination in a raceway, a base plate reversible face for face, a gib relatively fixed thereon, a second gib laterally adjustable with respect to the fixed gib and means for securing the gibs to the base 85 plate.

7. In combination in a raceway, a base 90 plate reversible face for face, a gib relatively fixed thereon, a second gib laterally adjustable with respect to the fixed gib, means for positioning and holding the gibs in alinement and means for securing the 95 gibs to the base plate.

8. In combination in a raceway, a base plate reversible face for face, a spline in each face thereof, a pair of gibs mounted on the said base plate, a spline in one of the gibs, a key coöperating with the splined gib in one of the splines in the base plate, means for adjustably positioning the other gib in alinement with the splined gib, and means for securing the gibs to the base 105 plate.
